UNITED STATES PATENT OFFICE.

ARTHUR ELLWOOD PLATT, OF OTTUMWA, IOWA.

HAY-STACKER.

SPECIFICATION forming part of Letters Patent No. 408,429, dated August 6, 1889.

Application filed April 9, 1889. Serial No. 306,577. (No model.)

To all whom it may concern:

Be it known that I, ARTHUR ELLWOOD PLATT, of Ottumwa, in the county of Wapello and State of Iowa, have invented a new and 5 useful improvement in Hay-Stackers, of which the following is a specification:

The invention consists in a new and improved hay-stacker, which will be hereinafter fully described and claimed.

Referring to the accompanying drawings, Figure 1 is a perspective view of my new and improved hay-stacker. Fig. 2 is a side elevation. Fig. 3 is a sectional detail view showing the fork, the front end of the beam, and 15 the catch for the said end. Fig. 4 is a detail view showing the catch for locking the beam in its upright position. Fig. 5 shows in detail the springs of the beam-axle, and Fig. 6 is a detail view of the catch for the front end 20 of the beam.

The same letters of reference indicate corresponding parts in all the figures.

Referring to the several parts by letter, A indicates the horizontal frame of the stacker, 25 on the ends of the cross-beams A' A' of which the supporting-wheels B are mounted.

C C indicate parallel upright frames on the main frame, and C' a cross-bar at the front of the same.

30 D indicates the swinging beam which carries the fork. This beam has the axle D², the rounded ends of which turn in bearings in the top of the frames C C. The front end or part D¹ of the beam is reduced in thickness and 35 curved at D³, as shown. On this reduced part of the beam is mounted the fork E, having the curved main forward teeth E' and the rear upright teeth E². When the fork is drawn back, the rear end of its frame E³ bears against 40 the shoulders d of the beam, and a spring- 45 catch d' holds the fork in that position, the arch D⁴ assisting in keeping the fork from running down on the lowered beam by its own weight.

45 The operating-rope F is fastened at one end to an eye f in the frame E³, passes forward and up over a pulley D¹, journaled in the front end of the beam, then back through a guide d⁵ on the beam, back between flaring guide- 50 pins d' at the rear end of the beam, down around the end of the beam, which is formed

with the guide-groove d⁶, and through pulleys d⁶ to the front of the frame, as shown.

In the recessed front end of the frame A is pivoted an L-shaped catch G, the long end of 55 which by its weight holds the catch end normally in a vertical position. An unlocking-plate H slides in a bearing on the beveled front end of the frame, its play being regulated by stops h h', the upright part of the 60 catch G fitting in the recessed front end of this plate, while the rear end of the plate is bent up at right angles.

The weight of the fork normally holds the front end of the beam down, with the point 65 of catch G engaged in a notch d⁷ in that end of the beam.

In operation, the fork being held back by spring-catch d', to raise a shock or load of hay or loose straw, the operating-rope F is drawn 70 forward, thereby drawing the fork forward free of the spring-catch, down along the beam D, so that its curved fingers E' will pierce and carry the hay. Just before the fork finishes its forward movement the lower cross-bar e of its head strikes the rear end of sliding plate H, and, pushing it forward, turns catch G so as to free it from the notched end of the beam. The pull of rope F then swings the beam D up, carrying with it the loaded fork, 75 which is held forward on the beam, as it is raised, by a shoulder d⁸ on the lower side of the same. When the hay is discharged from the fork as it is raised up and back to its far-thermost point, the hay slipping off the points 80 of the straight teeth E² will tilt the fork clear of the shoulder d⁸ of the beam, so that it will slip down the beam until it bears against the shoulders d and is caught and held by the spring-catch d'. The weight of a large fork 85 will of itself insure its slipping back into position, ready for the beam to be again lowered. The rope F being then slackened the beam will swing down again into its original position, when the notched front end of the beam 90 striking the rounded upper edge of the pivoted catch G will swing the upper part of catch out and cause it to engage with the notched end of the beam, ready to repeat the operations above described.

To the inner side of the upper part of one of the frames C are secured two springs I I', 100

the free upper ends of which are connected by ropes J J' with an eye I² on that end of the beam-axle. These springs operate as check-springs to reduce and prevent the jar 5 at the end of the upward and downward swing or movements, respectively, of the beam, as will be readily understood.

On each side of the front end of frame A are staples K, to which lines are attached 10 in moving the stacker from one place to another; also, stakes are driven through these staples into the ground to hold the stacker firm while in operation.

On the cross-bar C' is mounted a catch L, 15 the head of which can be caught in a flat staple L' at the side of the beam end, and will serve to hold the beam erect while clearing up hay or doing any kind of work under the fork. This catch has a rope L² secured 20 to its end, by pulling which the catch is freed from the beam, and this rope can be tied around the bar C' to hold the catch out of the way.

From the foregoing description, taken in 25 connection with the accompanying drawings, the construction, operation, and advantages of my invention will be readily understood. It will be seen that my new and improved hay-stacker is strong and comparatively simple in construction and exceedingly efficient 30 in its operation, being to a great extent automatic in loading and unloading itself. It is adapted particularly to stacking hay that is in shocks, as it will raise a shock at a time; 35 also, it is thoroughly adapted for taking straw away from a thrashing-machine and for stacking loose hay and hay in shocks.

Having thus described my invention, what I 40 claim, and desire to secure by Letters Patent, is—

1. In a hay-stacker, the combination, with the horizontal and upright frames, of the beam having the axle and the reduced curved forward part, the fork formed with the shank-frame E² and having the curved and straight teeth, and the operating-rope, substantially 45 as set forth.

2. In a hay-stacker, the combination, with

the horizontal and upright frames, of the beam having the axle, the spring, and the reduced forward part formed with the shoulders and having the pulley in its forward end, the fork having the curved and straight teeth, and the operating-rope, substantially 50 as set forth.

3. In a hay-stacker, the combination, with the horizontal frame having the pulleys and the upright frames, of the beam having the axle, the reduced forward part, and the shoulders, and having the pulley in its forward end, 55 and the recessed rear end, the spring and guides, the fork having the curved and straight teeth, and the operating-rope, substantially as set forth.

4. In a hay-stacker, the combination, with the horizontal and upright frames, of the beam having the axle, the spring, and the reduced forward part having the shoulders, the notched front end, and the pulley in its front end, the pivoted catch and the sliding plate, 60 the fork having the curved and straight teeth, and the operating-cord, substantially as set forth.

5. In a hay-stacker, the combination, with the horizontal and upright frames, of the 75 swinging beam having the axle and carrying the fork, and the check-springs I and I', secured at their lower ends to the upright frames and connected at their upper ends to the beam-axle by the ropes J and J', substantially as set forth.

6. In a hay-stacker, the combination, with the swinging beam having the flat staple on the side of its rear end, of the L-shaped catch adapted to engage with the same when 80 the beam is elevated, and the rope L², substantially as set forth.

7. In a hay-stacker, the combination of the horizontal frame having the staples at its forward end, the upright frames, and the swinging beam, the fork, and the operating-rope, 85 substantially as set forth.

ARTHUR ELLWOOD PLATT.
